UNITED STATES PATENT OFFICE

WILLIAM C. FORD, OF ANDOVER, MASSACHUSETTS

FOUNTAIN PEN

Application filed September 17, 1928. Serial No. 306,415.

This invention relates to fountain pens of the type having a hollow barrel which contains an ink reservoir usually a compressible rubber bulb, the outlet of which connects with and is adapted to feed a pen point carried at one end of the barrel.

As now made, such pens usually have a cap which protects the point while it is being carried in the pocket but which is removed and placed on the opposite end when writing.

Such pens also usually have some device on the side in the form of a lever by which the bulb can be compressed or released when it is desired to fill the pen.

It is well known that as such pens are usually carried with the point up, when one is taken out of the pocket and the cap removed for writing, the ink does not flow freely into the pen point and it is necessary to shake the pen, the result often being that a drop of ink falls out on the floor or a table.

The purpose of this invention is to provide a pen which can be taken out of the pocket and the cap removed from the pen end and placed on the other end after which by a simple and natural movement of the fingers or thumb, the bulb can be slightly compressed forcing a drop of ink out on to the pen without the necessity of shaking.

It is necessary however that the connection between the pressing device carried by the cap and the end of the pen should be such that when the cap is on the pen end, it will be substantially impossible for the bulb to be accidentally compressed thus inadvertently forcing out the ink.

I accomplish this purpose by providing inside the barrel, a compressor for the bulb and an operating member therefor movable in the barrel but having its head normally positioned inside the surface of the barrel so that it cannot accidentally be moved to operate the compressor.

I then provide a cap adapted to fit either end of the barrel so arranged that there is nothing to interfere with the pen end of the device entering the cap but so that when it is on the other end, transmitting means carried by the cap will be in position to engage the compressor operating member and one

or more pressure control members will be in convenient position for the fingers and thumb of the user to operate.

I may also provide means either in the barrel or the cap to normally limit the movements of the pressure control members and other means by which they can be released so that it or they can be moved sufficiently to fully operate the bulb compressor for filling the pen.

I prefer to arrange my devices so that by moving my pressure control member or members slightly, a drop of ink only will be forced out, but by moving them a greater distance, and then releasing them, the pen can be filled.

The opening for the compressor operating member may be in the round surface or the end surface of the barrel.

In the drawings, Fig. 1 is a view of my preferred construction with the cap on the pen end and as the pen appears attached to a pocket.

Fig. 2 is an enlarged view in section with the cap on the butt end, and the pressure control member in operative position.

Fig. 3 is a similar sectional view showing a slight modification of the contact end of the transmitting member.

Fig. 4 is a detail showing a guiding device.

Fig. 5 is a view similar to Fig. 2 showing a modified construction.

Fig. 6 shows another modification.

Fig. 6A is a vertical sectional detail of a very much simplified construction.

Fig. 6B is a plan view of the construction shown in Fig. 6A.

Fig. 6C is a side elevation of Fig. 6B.

Fig. 7 shows a detail of another type of compressing device.

Fig. 8 shows a pen of a modified construction as it is held in one hand in the process of filling the pen.

Fig. 9 is a view similar to Fig. 8 showing one position of the hand when starting a drop of ink when beginning to write.

Fig. 10 is a sectional elevation of the type of pen shown in Figs. 8 and 9 with the cap on the butt end.

Fig. 11 is a vertical section at right angles

to Fig. 10 showing a bulb being compressed for filling.

Fig. 12 is a view similar to Fig. 10 showing the cap on the pen point end of the pen.

5 L represents the barrel of a pen having at one end 60 the pen point B, the other end 61 being closed. As shown in Fig. 2, there is in the surface at the side, an opening 130 into which there projects but not through, an operating member 133 for compressor 131 which is a strip of substantially rigid metal which preferably conforms to the curve of the inside of the barrel L and bulb C.

15 The cap M when on the pen end 60 may be in any position around the circumference but when on the other end as shown in Fig. 4 is preferably guided into position by means of the V-shaped slot 138 in its end 137 together with a pin 139 which projects from the barrel L.

20 N represents a combination of a pressure control member and transmitting means, being an elastic strip of metal fixed at 134 to cap M and of sufficient length in the shank 25 135 so that it extends beyond the open end 65 of cap M. It terminates in a neck 132 at right angles and in a ball 136.

As shown in Fig. 1, when the cap is on the pen end, the part N can be used as a clip to 30 pass over the edge 64 of cloth P of the pocket and will hold the pen in position.

When however it is on the butt end 61 of barrel L, it is guided to the proper position by pin 139 so that the ball 136 will register 35 with opening 130 but will not enter that opening unless pressed in by the fingers, as shown by the dotted lines in Fig. 2, when it will force inward the operating member 133 of the compressor 131 thereby squeezing the bulb C as much or as little as desired. Thereby a 40 single drop of ink can be forced out or the bulb can be compressed and the pen can be filled when pressure is removed.

Fig. 3 shows a slight modification wherein 45 the transmitting member 145 is bent down at 146 to form a contact member to enter an opening 130, in place of the ball.

147 is a controlling ring having a cut away part 148. The ring 147 can be moved around 50 so as to limit the movement of 146 so that a drop only will be squeezed out, or the slot 148 can be brought in position so that a greater squeeze can be made.

If desired, a sliding protecting ring such 55 as 248 shown in Fig. 2 can be used. This can be slid along to completely cover opening 130 if desired.

In Fig. 5, I show my device adapted to a well known type of pen wherein the bulb C in barrel A is compressed by means of a metal strip 230 which is forced in by means of a lever 231 pivoted on the side of the pen.

60 In this device, I use a plunger 120, slideable inside barrel A, which is ordinarily in contact with the end of bulb C which serves the

purpose of a returning spring whereby it is kept normally just a little inside of the end 110.

In the cap G is slideable a piston 121 from which extend the legs 124 and 125 of such length that when cap G is in place they will engage plunger 120. This piston 121 extends out from the end 123 in its normal position and spreads out in the form of a cap 122 which serves as a pressure control member and as a stop to limit the movement of 121 and therefore of 120 to the position shown in the dotted line. This push button type as shown is adapted only for starting but by increasing the distance from 123 to 122 can be used also for filling.

70 In Fig. 6, I show a bulb or reservoir 90 the end of which 91 is concave to receive the compressor, or compressing member 92 which is fixed to plunger 93 the head of which 94 is normally a short distance from the outside of the chamfered end 110 of barrel A and from the ends of the transmitting members 124, 125. Compressor 92 is forced inward by the transmitting members, and the end 91 assumes the form shown by the dotted lines causing the ink to flow when starting to write or to compress the bulb in the process of filling.

75 In Fig. 7, I show another type of compressing means consisting of the two spring legs 100 and 101 bent around the pin 102 and extending down on each side of the bulb C. The plunger 103 is positioned a little inside of the end 110 of barrel A and has two legs 104 and 105 which are joined together by a ring 106 which slips over spring legs 100 and 101 the parts being so formed that when 103 is pushed in, ring 106 forces legs 100 and 101 together thus squeezing bulb C. 107 is a returning spring for the plunger.

80 In Figs. 8 to 12 I show a push button type of pen in which the various parts are accurately defined and located.

A represents the tubular barrel of a fountain pen which carries at one end 10 the pen point B and terminates at 11 at the other end, there being an annular recess 12 at this end, which might be called the butt end. 13 represents the inside of the barrel and 15 an inside stop for plunger spring 32 while 14 represents an outside stop to limit the movement of the cap G.

C represents a compressible bulb, the neck of which feeds pen point B and which can be compressed by the compressor D.

85 This compressor may be of various types such as shown in the other views but it is desirable if not necessary that it should be capable of compressing the bulb when the plunger such as F is moved in from the butt end.

90 As shown in Fig. 10, it comprises stem 31 and an elastic or bendable strip 120 of metal fastened inside barrel A at 20 and then ex-

tending back to the point 25 which together with 15 serves as a stop or support for spring 32. From thence it extends at an angle at 21 and thence at another angle 22 between the bulb C and the inside 13 of barrel A.

Plunger F comprises a head 30 slidible inside barrel A and with the end 33 of its head positioned normally inside the end 11 of barrel A and a little beyond the annular recess 12 which serves to limit the movement of push button H in a manner to be described. End 11 preferably is chamfered inside.

31 is a stem extending from head 30 of plunger F in normal engagement with the sloping part 21 of strip 120. The limits of movement of plunger F are determined by a slot such as 36 into which enters a pin 16 which passes through barrel A.

The cap G is of a size so that it is adapted to fit either end of the barrel, its inside diameter 41 being of substantially the same size as the outside 17 of barrel A.

Its position on the butt end is regulated by its end 44 engaging the stop 14 on barrel A.

On opposite sides are the holes 42, 42, through which pass the release buttons 49, 49 adapted to allow the push button H to move a greater distance than ordinarily.

This push button H is preferably hollow and has a closed end 50 which projects out from the end 40 of cap G.

Between its other end 54 and the release buttons 49 is a light compression spring 55 which keeps the end 50 ordinarily projecting from end 40.

52, 52 are what I will call transmitting members which are strips of spring metal fastened at 53 oppositely on the inside of push button H and extending down to the bent ends 56, 56 which are of such length that ordinarily they both engage the end 33 of head 30 at a point a slight distance away from the limiting annular stop 12.

When first using the pen to write as shown in Fig. 9, it is held in the four fingers 2, 3, 4 and 5 while the thumb 1 presses on button H moving it in the distance between 56 and 12 thus compressing the bulb C slightly and forcing out a drop of ink.

When however it is desired to fill the pen, it can be held with the fingers 3, 4 and 5 and the thumb 1, the thumb and finger 3 pressing in on release buttons 49, 49 so that the finger 2 can press the push button H in and as the transmitting means or legs 52, 52 are moved inside stop 12 as shown by the dotted lines in Fig. 10, they together with plunger F with its stem 31 can move a greater distance thus compressing bulb C a larger amount when it is desired to fill the pen.

As shown in Fig. 12 the cap G can be put on the opposite end of the pen and its construction is such that it will not interfere with the point B.

In the construction shown in Figs. 8, 9, 10,

11, 12, D is the compressor, F and its accessories is the operating member, 11 is the opening therefor, G the cap, H the pressure control member while 52, 52, 49, 49 comprise the transmitting means.

In Figs. 6A, 6B and 6C, I show a very much simplified device which can be used if desired.

The bulb C is of the same type as shown in Figs. 2, 3 and 5 and the barrel L is of the usual type with a compressor opening 330 similar to 130 and performing the same function as 11 the compressor 331 being positioned in line with hole 330 and is shown as coming close to its inside. When cap M is on the end of the barrel which is opposite the pen point the guide opening 340 for the transmitting member 341 registers with compressor opening 330.

This transmitting member is shown as a shank 341 slidible in a guide opening 342 forming an outlet for 340 and member 341 terminates in the conical head 343 the parts being of such size and position that the whole of 343 can be housed in guide opening 340 as shown by the dotted lines when the pressure control member 344 shown as a push button head is moved out to the dotted line position.

With this construction it is not necessary to have any returning spring as the member 344 can move in and out loosely when the cap M is on the pen end and when it is positioned on the other end of the barrel, the conical surface of the part 343 causes the part to move out so that cap M can be slipped on without difficulty. When the openings 340 and 330 register however, the pressure control member 344 can be pressed in more or less transmitting the pressure through members 341 and 343 to the compressor 331, which has no head, and thence to bulb C. The natural elasticity of bulb C or the spring of compressor 331 will bring the parts back in place when released.

The device shown in Fig. 6A reduces the number of operating parts to the minimum.

Member 344 can be positioned near the disc shaped end 346 common on such caps as M or it can be positioned in an extension thereof 345 as shown in Figs. 6B and 6C.

As shown in Fig. 6C this construction has the advantage that the part 343 is exposed and that cap M can be put on barrel L by starting it at an angle and then straightening it out as shown by the dotted lines.

I claim:

1. The combination with a fountain pen having a barrel which contains a compressible bulb adapted to feed a pen point carried at one end of the barrel; of a compressor positioned inside the barrel and adapted to compress the bulb; an operating member for the compressor movable in an opening in the side of the barrel and having its head normally positioned inside the surface of the

5 barrel, said member being in engagement with the compressor; a cap adapted to fit either end of the barrel; a pressure control member and transmitting member consisting of an elastic shank fixed to the outside of the cap and extending beyond the open end of the cap in position to register with the opening in the side of the barrel when the cap is on that end of the barrel which is opposite the pen point.

10 2. The combination with a fountain pen having a barrel which contains a compressible bulb adapted to feed a pen point carried at one end of the barrel; of a compressor positioned inside the barrel and adapted to compress the bulb; an operating member for the compressor movable in an opening in the side of the barrel; a cap adapted to fit either end of the barrel; a pressure control member 15 and transmitting member consisting of an elastic shank fixed to the outside of the cap and extending beyond the open end of the cap in position to register with the opening in the side of the barrel when the cap is on that end of the barrel which is opposite the pen point.

20 3. The combination with a fountain pen having a barrel which contains a compressible bulb adapted to feed a pen point carried at one end of the barrel; of a compressor positioned inside the barrel and adapted to compress the bulb; an operating member for the compressor movable in an opening in the barrel and having its head normally positioned inside the surface of the barrel, said member being in engagement with the compressor; a cap adapted to fit either end of the barrel; a pressure control member carried by the cap; and transmitting means movable 25 by the pressure control member adapted to engage the compressor operating member when the cap is on that end of the barrel which is opposite the pen point.

4. The combination with a fountain pen 30 having a barrel which contains a compressible bulb adapted to feed a pen point carried at one end of the barrel; of a compressor positioned inside the barrel and adapted to compress the bulb; an operating member for the compressor movable in an opening in the barrel; a cap adapted to fit either end of the barrel; a pressure control member carried by the cap; and transmitting means movable by the pressure control member adapted to engage the compressor operating member when the cap is on that end of the barrel which is opposite the pen point.

35 5. The combination with a fountain pen having a barrel which contains a compressible reservoir adapted to feed a pen point carried at one end of the barrel, said barrel having a compressor opening; of a compressor inside the barrel and adapted to compress the reservoir, said compressor being positioned in line with the compressor open-

ing; a cap adapted to fit either end of the barrel; a pressure control member carried by the cap; and transmitting means movable by the pressure control member and adapted to engage the compressor when the cap is on the 70 end of the barrel which is opposite the pen point.

6. The combination with a fountain pen having a barrel which contains a compressible bulb adapted to feed a pen point carried at 75 one end of the barrel, said barrel having a compressor opening; of a compressor inside the barrel adapted to compress the bulb and positioned in line with said compressor opening; a cap adapted to fit either end of the 80 barrel; a pressure control member carried by the cap; and a transmitting member carried by the cap and connected with the pressure control member in position to register with the compressor opening when the cap is 85 on that end of the barrel which is opposite the pen point.

7. The combination with a fountain pen having a barrel which contains a compressible bulb adapted to feed a pen point carried at 90 one end of the barrel and having an opening in the side of the barrel; of a compressor positioned inside the barrel adjoining the opening in the barrel, said compressor being adapted to compress the bulb; a cap adapted 95 to fit either end of the barrel, a pressure control member and transmitting member consisting of an elastic shank fixed to the outside of the cap and extending beyond the open end of the cap and having a contact member 100 in position to register with the opening in the side of the barrel when the cap is opposite that end of the barrel which is opposite the pen point; and a stop device adapted to limit the movement of the contact member.

8. The combination with a fountain pen having a barrel with an opening in the side, which barrel contains a compressible bulb adapted to feed a pen point carried at one end of the barrel; of a compressor positioned 110 inside the barrel and adapted to compress the bulb; a pressure control and transmitting member which comprises a contact member adjoining the opening in the side of the barrel and adapted to pass through such opening 115 and engage the compressor; and a stop device adapted to limit the movement of the contact member.
